UNITED STATES PATENT OFFICE.

WILLIAM F. GOELTZ, OF WATERBURY, CONNECTICUT, ASSIGNOR TO GEORGE II. CLOWES, OF SAME PLACE.

DESIGN FOR A LAMP-BRACKET.

SPECIFICATION forming part of Design No. 29,407, dated September 27, 1898.

Application filed March 14, 1898. Serial No. 673,871. Term of patent 14 years.

To all whom it may concern:

Be it known that I, WILLIAM F. GOELTZ, a citizen of the United States, residing at Waterbury, in the county of New Haven and State 5 of Connecticut, have invented and produced a new and original Design for Lamp-Brackets, of which the following is a specification, reference being had therein to the accompanying drawings.

10 In the accompanying drawings, Figure 1 is a plan view of the bracket-arm, and Fig. 2 is a side elevation thereof.

15 The leading feature of my design consists of an arm for a bracket provided at one end with a V-shaped recess and with a similar V-shaped recess of a greater angle at the opposite end thereof, the said recesses being united by a straight and an angular web portion.

20 Referring to the drawings, the letter A designates the arm, provided at one end with the V-shaped recess 1 and with the V-shaped recess 2 of a greater angle at the opposite end thereof, the web between said recesses being

composed of the straight portion 3 and the angular portion 4. Upon the front side the 25 bracket-arm is provided with the centrally-disposed rounded rib 5, extending from the inner wall of recess 1 to the inner wall of the recess 2, with two ribs 6 6 of smaller cross-section extending transversely across the two 30 walls of recess 1, near the side edges of the arm, and with two similar ribs 7 7, extending transversely across the two walls of recess 2, near the side edges of the arm.

Having described my invention, what I 35 claim as new, and desire to secure by Letters Patent, is—

The design for a bracket-arm, substantially as herein shown and described.

In testimony whereof I affix my signature 40 in presence of two witnesses.

WILLIAM F. GOELTZ.
